UNITED STATES PATENT OFFICE.

CHARLES W. LINDE, OF SLATER, COLORADO.

FLASH-BOILER.

No. 867,281.

Specification of Letters Patent.

Patented Oct. 1, 1907.

Application filed April 4, 1907. Serial No. 366,425.

To all whom it may concern:

Be it known that I, CHARLES W. LINDE, a citizen of the United States, residing at Slater, in the county of Routt and State of Colorado, have invented a new and 5 useful Flash-Boiler, of which the following is a specification.

This invention has relation to flash boilers and it consists in the novel construction and arrangement of its parts as hereinafter shown and described.

10 The object of the invention is to provide a boiler which is adapted to flash water into steam and which is provided with an automatic means for supplying the water to the boiler; said means being so arranged and equipped that the water is cut off when the steam 15 within the boiler becomes too great or the quantity of water too large. That is to say, that excess of steam pressure or excess of quantity of water the supply of water is cut off.

The boiler consists of a series of units in the form of 20 coils which are connected together and which are provided with valves whereby any particular unit may be cut out of the boiler without relieving the other units of the pressure incidental to the performance of their functions as steam generators.

25 In the accompanying drawings:—Figure 1 is a side elevation of the boiler with one side of the casing removed. Fig. 2 is a similar view of the boiler from the opposite side. Fig. 3 is a top plan view of the boiler with the top of the casing removed. Fig. 4 is a top 30 plan view of one of the units used in the boiler, and Fig. 5 is a vertical sectional view of a float mechanism used in connection with the boiler for regulating the flow of water.

The boiler comprises the casing 1 which is provided 35 at one end with the doors 2, 2 and in its interior with the baffle plates 3. Said casing is also provided with a fire box and grate 4 and a stack 5. The said casing forms a means for circulating and confining heat about the steam generators proper. The said generators are 40 in the form of units designated as *a*, *b*, *c*, *d*, *e*, *f*, *g*, *h*, *i*, *j*, *k* respectively and lying in parallel planes one above the other and within the casing 1 and about the baffle plates 3. Each unit is made up of a coil 6, one end of which is connected by means of a pipe section 6' with 45 the transversely disposed pipe 7 which is located above the coil and which connects at its other end by means of a pipe section 6'' with the next lower coil in the manner as illustrated in Figs. 1 and 2 of the drawing. Thus, each unit consists of a coil lying in a plane and a trans- 50 verse section in elevated position with relation to the coil. The coils are so connected up in the arrangement of the generators or units that the water is first introduced into the upper unit *a* and from said unit into the next lower unit *b* and so on down through the 55 entire set, an exception being provided at an intermediate unit *j* as will be hereinafter explained. The

fitting at the ends of the transverse sections 7 are provided with the valves 8 and all of the sections 7 (which lie in the same plane) are connected together by a pipe section 9. The section 9 is provided with the valves 60 10 which are located between adjacent transverse sections 7. By this arrangement of pipe sections and valves it is possible to cut out any particular unit without interfering with the circulation of water or steam through the remaining units.

As shown in Fig. 1 the pipe section 7' connects with the upper end of a cylinder 11, the lower end of which connects with the unit *j*, which is next to the lowest unit in the series. The perforated plates 12 are located in the cylinder 11 near the upper and lower ends thereof. The float 13 is located in the cylinder 11 and is provided at its upper end with a rod 14 which passes through the center of the upper plate 11. The tube 15 is connected to the lower end of the float 13 and communicates with the interior thereof. Said tube is open 75 at both ends and passes through the center of the lower plate 12. The rod 14 and tube 15 serve as guides for the float 13 and the plates 12, 12 limit the longitudinal movement of the float within the cylinder 11. The crank shaft 16 is journaled in a lateral projection of the 80 cylinder 11 and has one of its ends connected with the rod 14 and its other end with a rod 17 which in turn is connected with the stem of a throttle valve 18. The pump 19 is supported at any convenient point and is connected with the water supply pipe 20. The pipe 85 21 connects said pump with the upper unit *a* of the generator. The lowest unit *k* of the generator is connected with the steam pipe 22 which in turn is provided with a branch 23 which leads to the pump 19 and conveys steam to the same. Pipe 24 connects with the 90 pump 19 and is for conveying condensed steam away from the same. The valve 18 is located upon the pipe 23 as is also the valve 25. The safety valve 26 is mounted upon the steam pipe 22 and is provided with a laterally disposed cylinder 27 in which is located a piston 95 28 attached to the piston rod 29. The outer end of the piston rod 29 is pivotally connected to one end of the lever 30 and the rod 31 is pivoted at one end to the other end of said lever and at its other end to the stem of the valve 25. The valve 25 is open so long as the 100 valve 26 is closed but through the connection above described closes as soon as the valve 26 opens. The valve 18 is open while the float 13 is in its lowermost position but the said valve 18 is closed by means of its connections when the said float 13 rises.

From the foregoing description of the arrangement of parts it is obvious that should the quantity of water within the boiler become excessive and thereby prevent the speedy conversion into steam the water will descend through the pipe section 7' and fill the unit *j*, 110 which is next to the lowest unit in the series. As the water rises in the said unit *j*, and through its connection

in the cylinder 11 the float 13 will be elevated which will swing the shaft 16 and move the rod 17 longitudinally which will turn the valve 18 and cut off the steam through the pipe 23 to the pump 19. Thus the said 5 pump will cease operating and the supply of water to the boiler will be cut off and will remain cut off until the water in the boiler is converted into steam to such an extent as to permit the float 13 to fall when the operation last above described is reversed and the pump 10 10 will begin to supply water to the boiler as above described. When the steam pressure within the boiler becomes excessive the steam escapes from the pipe 22 through the valve 26 and enters the cylinder 27. The piston 28 is moved longitudinally of the cylinder and 15 through the piston rod 29 the lever 30 is swung upon its fulcrum which in turn moves the rod 31 longitudinally and closes the valve 25. Thus the steam is cut off from the pump 19 and it ceases operating and remains in a state of inactivity until the steam pressure has been reduced 20 in the boiler and pipe 22.

When it is desired to cut any particular unit out of the circuit, for repair or other purposes, the valve 10 in the pipe 9 located between the section 7 of the unit to be cut out and the section 7 of the next adjacent unit is 25 opened and the valve 8 at the end of the section 7 nearest the coil 6 of the unit to be cut out is closed. Thus the said unit is cut out of the circuit while the water or steam, as the case may be, will pass along a portion of the section 7 and through the pipe 9 into the adjacent 30 unit and then throughout the remaining units. For instance if it is desired to cut the unit b out of the circuit of the series of units, the valve 8, at the upper end of the pipe section 6² connecting with the unit b is closed and

the valve 10 on the pipe 9 which is between the pipes 7, 7 which are connected with units a and b, is opened. 35 The valve 8 at the upper end of the pipe section 6² which connects with the unit b is closed. Thus both ends of the unit b are closed by the valves 8, 8 and the fluid passes from the unit a to unit c, through pipe 9 and the opened valve 10. Thus the pipe 9 serves as a by-path between the several units and is normally closed at points between the several units. 40

Having described my invention what I claim as new and desire to secure by Letters-Patent is:—

1. In a boiler, a unit consisting of a coil lying in a 45 plane, a transverse section lying parallel with the plane of the coil and a connecting section at a right angle to the plane of the coil and the transverse section.

2. A boiler comprising a series of units each consisting of a coil lying in a plane, said coils being arranged one 50 above the other and sections leading from each unit and passing over the same and connecting with the next lower unit.

3. A boiler consisting of a series of units arranged one 55 above the other, connections between the units which extend transversely and lie in a plane above all of the units, a pipe connecting all of said connections together and valves located upon the pipe between the connections.

4. A boiler comprising a series of units having inter-connecting sections, said sections being provided with 60 means whereby any particular unit may be cut out of the circuit.

In testimony that I claim the foregoing as my own, I have hereto affixed my signature in the presence of two witnesses.

CHARLES W. LINDE.
